RAILWAY TRUCK

Glenn F. Couch, Rochester, N. Y., assignor to
 The Symington Company, Rochester, N. Y., a
 corporation of Maryland

Application May 23, 1928, Serial No. 279,974

22 Claims. (Cl. 105—186)

This invention relates to railway trucks, and more particularly to a side frame provided with a bridge wall connecting the lower portions of the bolster guide columns thereof in combination 5 with a laterally movable bolster.

The principal object of my invention, generally considered, is to provide a railway truck in which the side frames of the bridge type such as shown in Richards application, Serial No. 135,442, now 10 Patent No. 1,843,069, dated January 26, 1932, that is, formed with bridge walls connecting the lower portions of the bolster guide columns or struts, whereby the strength thereof is greatly increased and the springs protected against oversolid blows, 15 the size of the bolster opening being at the same time decreased, whereby the associated bolster can not be inserted and removed in the conventional manner, springs and a spring cap being supported by each frame and lateral motion rollers being disposed between said spring caps and the adjacent ends of the associated bolster, the 20 construction being such that the caps are interlocked with the frame and the bolster is in turn interlocked with the caps for limiting lateral movement thereof.

Another object of my invention is to provide a bridge type side frame in which the bolster springs on opposite sides of the bridge support a spring cap, which in turn supports rollers disposed between said cap and bolster whereby lateral movement of said bolster is permitted, the 25 construction being such that the spring cap is interlocked with the frame and the bolster interlocked with the spring cap.

A further object of my invention is the provision of a railway truck involving side frames and a lateral motion bolster in which the bolster has standard transverse movement before its inner stops engage the bolster guide columns, said 30 bolster being formed without the usual outer stops and adapted to receive upstanding lugs on a spring cap for limiting relative transverse movement thereof.

A still further object of my invention is to 35 devise an improved interlocking relationship between a lateral motion bolster and the associated side frames in which said frames have strengthening bridge portions between the lower parts of the bolster guide columns, the parts being assembled by inserting an upper spring cap diagonally 40 in the bolster opening and then letting it down flat on the bridge with its guiding lugs engaging the bolster guide columns, the lateral motion rollers being then inserted, after which the bolster 45 is applied thereabove, said bolster, rollers and cap

then raised and the springs applied therebeneath, the construction of the parts being such that the bolster cannot get off the interlocking stop lugs on the cap while the springs are in position.

Other objects and advantages of the invention 5 relating to the particular arrangement and construction of the various parts will become apparent as the description proceeds.

Referring to the drawings illustrating my invention, the scope whereof is defined by the ap- 10 pended claims.

Figure 1 is a partial plan and partial horizontal sectional view of a fragmentary portion of one embodiment of my truck, particular illustrating the connection between the bolster and an asso- 15 ciated side frame.

Figure 2 is a side elevation of a fragmentary portion of the side frame and bolster illustrated in Figure 1, a portion of the bolster and spring cap being shown in vertical section.

Figure 3 is a transverse sectional view of that 20 portion of the truck shown in Figures 1 and 2, the bolster springs being diagrammatically indicated by dot and dash lines.

Figure 4 is a side elevational view of the bolster 25 and spring cap interlocked therewith, the lateral motion rollers being shown in position therebetween.

Figure 5 is a plan of the spring cap.

Referring to the drawings in detail, like parts 30 being designated by like reference characters, a truck side frame 1 of the cast type is shown, although it will be obvious that certain advantages of my invention may be secured using frames of other construction. Said frame 1 com- 35 prises a compression member 2, a tension member 3 and bolster guide columns or strut portions 4 spacing intermediate portions of said compres- 40 sion and tension members, leaving a bolster or window opening 5 therebetween. The compres- 45 sion and tension members extend outwardly in the usual manner and are joined to each other adjacent the ends of the frames (not shown) and either have integral journal boxes at said ends or are adapted for being securely connected to 50 associated journal boxes (not shown).

For rigidifying the construction of the frame the lower portions of the bolster guide columns or struts 4 are preferably rigidly connected by means of a double-walled bridge portion, wall 50 or girder 6, extending from the upper web 9 of the intermediate or horizontal portion 10 of the tension member 3, said girder in the present em- 55 bodiment being formed with vertical web portions 7 connected at the top by a transverse web por-

tion 8 which extends at an angle to the web portions 7 and presents a flat top surface of relatively great area as compared with the horizontal section of one of the web portions 7. The bolster guiding portions of the bolster guide columns 4 at opposite ends of the bridge wall 6 are substantially channel-shaped in cross-section, said channel shape, however, being preferably of special form involving a transverse web 11, and 10 diagonally disposed or flaring flanges 12, the outer ends of said flanges, however, being extended longitudinally of the frame, as indicated at 13.

On opposite sides of the bridge wall 6, which 15 may be considered as an upward convolution of the upper web 9 of the horizontal portion 10 of the tension member 3, said web 9 is preferably extended outwardly beyond the sides 14 of the tension member to provide sufficient area for 20 supporting the bolster springs 15, indicated grammatically by dot and dash lines; see particularly Figure 3. Those portions of the upper web 9 beyond the sides 14 of the tension member are preferably braced or rigidified with respect 25 to the sides 14 by means of the triangular gusset portions. The upper surface of the web 9 of the tension member is desirably formed with upstanding lugs 16 adapted to serve as spring positioning means, that is, to fit within the bolster springs 15 and maintain the same in proper position. The inner lugs 16, that is, those disposed 30 inwardly of the bridge wall 6, preferably also serve as spring plank squaring lugs for maintaining the associated spring plank 17 in proper relation with respect to the frame. For that purpose they desirably extend through corresponding apertures 18 in the lower web of the plank 17, said apertures being preferably larger than the normal size of the lugs 16, the bases of said 35 inner lugs 16 being correspondingly increased, as indicated at 19, for filling the apertures 18 in said spring plank.

The bolster springs 15 are supported by means of the upper web 9 of the tension member, the 40 outer springs resting directly on said upper web and the inner springs preferably resting on the web of the spring plank 17, whereby said spring plank is retained in position on the frame. The upper web 9 of the tension member beneath the 45 spring plank is desirably slightly lower than the outer portion of said web, so that the top of the spring plank, when in position, is on the same level as the top of the outer portion of the upper web 9 of said tension member, whereby all of the 50 bolster springs may be of the same height.

Resting directly on the tops of the springs 15 is a spring cap or seat 20, the lower surface of which is provided with depending flange or rib portions 21 which extend over the tops of the 55 associated springs 15 and retain said springs and cap in the desired assembled relation. The cap is prevented from undesired lateral movement with respect to the frame by outstanding lug or guiding portions 22 which are correspondingly 60 beveled and engage the sides 12 of the guide columns whereby vertical but not relative transverse movement of said cap is permitted. The upper surface of said cap is desirably formed with concave roller-receiving portions 23 and the lower 65 surface of the supported bolster 24 is correspondingly formed with roller-receiving portions 25. Rollers 26 are employed between the bolster 24 and the spring cap 20 whereby limited lateral 70 movement of the bolster with respect to the 75 spring cap and associated frame is permitted.

On account of the engagement between the rollers and the concave portions of the bolster and cap, said bolster tends to return to normal position, as any movement from normal involves a raising of the bolster and the supported body of 5 the car.

In order to limit lateral movement of the bolster with respect to the frame, said bolster is formed with inner stops 27, which engage the bolster guide columns after the standard or normal permitted transverse movement of said bolster. No outer guide lugs are provided on the bolster because on account of the bridge wall 6 it would be impossible to insert said bolster in place if such lugs were provided. Instead the 10 bolster is formed with downwardly opening pockets or insets 28 and the spring cap 20 is provided with correspondingly formed, upstanding lug or flange portions 29 fitting in the pockets 15 while permitting normal relative movement between said bolster and cap. From a consideration of Figure 4, particularly, it will be seen that the lug or flange portions 29 on the cap involve outermost lug extensions 30, which are preferably the highest parts of the lug 29 and fit in the 20 tallest portions 31 of the receiving pockets or inset portions 28 of the bolster, the portions 31 of the bolster, however, being sufficiently wide to permit the desired transverse movement of the 25 bolster. Inwardly of the lug portions 30 the 30 flanges 29 are continued at reduced height as indicated at 32 and near their innermost ends are formed with shouldered or cut-away portions 33 receiving correspondingly shouldered portions 34 on the bolster, with the provision of similar 35 clearance for permitting the desired lateral motion of said bolster. It will therefore be seen that the spring cap is interlocked with respect to the bolster by the engagement of the extended lug portion 30 in the pocket portion 31, which 40 serves to limit movement of the bolster both ways, movement of the bolster outwardly of the frame being limited also by the engagement between the shoulder 34 thereon in the shouldered portion 33 of the spring cap, as well as by engagement 45 between the inner stop lugs 27 and the bolster guide columns 4.

From the foregoing it will be seen that I have devised a bridge type side frame with a spring cap and rollers permitting lateral movement of the 50 associated bolster, while at the same time interlocking said bolster with respect to the frame. In order to assemble the parts in place the spring cap or seat 20 is inserted diagonally in the bolster or window opening 5 and let down to a horizontal position on the top of the bridge 6. The rollers, which in the present embodiment are four in number, although it will be obvious that more or less may be employed, are then placed in position and the bolster inserted thereabove. The 55 parts are so designed that when the bolster is in the extreme upper portion of the bolster opening 5 it will clear the lug portions 30 on the cap 20, when said cap is resting on the top of the bridge 6. The spring cap 20 and the associated rollers 60 and bolster are then raised and the springs applied therebeneath, the inner springs, of course, resting on the associated spring plank 17. The parts are so designed that the bolster cannot get off the stop lugs 30 while the springs are in position. 65

Although a preferred embodiment of my invention has been illustrated, it will be understood that modifications may be made within the spirit and scope of the appended claims.

and interlocked with the frame for preventing lateral movement thereof, rollers supported on said cap, a bolster with its end supported on said rollers, said cap being provided with stop lugs engaged in corresponding pockets in the bolster for limiting transverse movement of the latter.

10. In a railway truck, in combination, a side frame with a tension member and bolster guide columns rigidified by a bridge wall connecting the lower portions of said guide columns, springs supported on said tension member on opposite sides of said bridge wall, a spring cap resting on said springs above said wall, said spring cap being interlocked with the bolster guide columns for restraining lateral movement of said cap while guiding it for vertical movement, lateral motion antifriction means resting on said cap, and a bolster resting on said means, the movement of said bolster being limited by engagement of an upstanding lug on the cap in a corresponding downwardly opening pocket in said bolster.

11. The method of assembling a lateral motion bolster with a bridge type side frame, comprising inserting an upper spring cap diagonally in the bolster opening of the frame and letting it down flat on the bridge, applying lateral motion rollers thereabove, inserting the bolster in the bolster opening above said rollers, raising said bolster, rollers and cap, applying the bolster springs beneath said cap and above the tension member of the frame, and lowering said cap, rollers and bolster on said springs.

12. In a railway truck, in combination, a side frame formed with a bolster opening, bolster springs positioned in said opening, a bolster disposed above said springs, the end of said bolster being so formed that it is freely insertable in said opening, a spring cap resting on said springs and formed with portions engaging the parts of the frame defining the sides of said opening for limiting lateral movement thereof while permitting vertical movement, and rollers disposed between said bolster and cap, interlocking portions being provided on said latter members for limiting movement of said bolster transversely of the side frame.

13. In a railway truck, in combination, a side frame formed with a bolster opening, bolster springs, a spring cap resting on the tops of said springs and interlocked with the frame for preventing lateral movement thereof, rollers supported on said cap, a bolster with its end supported on said rollers, said cap being provided with stop lugs engaged in corresponding pockets in the bolster for limiting transverse movement of the latter.

14. In a railway truck, in combination, a side frame, bolster springs supported thereon, a spring cap resting on said springs, said spring cap being interlocked with portions of the frame for restraining lateral movement of said cap while guiding it for vertical movement, lateral motion antifriction means resting on said cap, and a bolster resting on said means, the movement of said bolster being limited by engagement of an upstanding lug on the cap in a corresponding downwardly opening pocket in said bolster.

15. In a car truck, a bolster, a side frame having a central opening with vertical columns at the sides thereof adapted to receive an end of the bolster therebetween, said bolster having inner stops adapted to engage said columns and limit movement of the bolster into said opening, means removably mounted in said bolster and comprising flanges closely engaging the outer

surfaces of said columns, cooperating with the bolster and supplementing said inner stops, springs on the side frame for supporting the bolster, and maintaining said removable means in position in said bolster, a member mounted on said springs and provided with anti-friction elements directly supporting said bolster for movement laterally of the side frame, and means projecting downwardly from said member for holding said springs in position.

16. In a railway vehicle truck, in combination, a side frame having a central opening and normally vertical columns at the sides thereof, a web disposed below said opening for reinforcing said frame, a bolster having one of its ends extending into said opening, springs supported on said frame on either side of said web, a spring cap member in said opening and normally supported by said springs, said spring cap member being formed to support the associated end of the bolster and permit lateral movement thereof with respect to the frame, and means normally extending vertically and serving to limit said lateral movement of the bolster, said bolster being recessed and normally receiving said movement-limiting means, said cap member having guide channels normally receiving portions of said columns and interlocking said member with respect to said frame.

17. In a car truck, a bolster, a side frame having a tension member with an upper web and a window opening thereabove with vertical columns at the sides thereof adapted to receive an end of the bolster therebetween, the upper web of the tension member being upwardly convoluted below the window opening to provide a double-walled bridge portion between the columns for reinforcing said side frame, springs on said frame on either side of said bridge portion, and means above said springs and including parts adapted to roll on a lower wall of said bolster, a spring cap, and interlocking portions extending between said cap and bolster, whereby the latter is mounted for limited movement laterally of the side frame.

18. In a car truck, a bolster, a side frame having a central opening with vertical columns at the sides thereof adapted to receive an end of the bolster therebetween, means removably mounted beneath, and comprising flanges interlocking with, said bolster and adapted to engage said columns, springs on the side frame for supporting the bolster and maintaining said removable means in position in said bolster, and a plurality of rollers extending for the major part of the bolster width, spaced longitudinally of and directly engaging a lower wall portion of said bolster and disposed above said springs, whereby the bolster is supported for movement laterally with respect to the side frame.

19. In a car truck, a bolster, a side frame having a central opening with vertical columns at the sides thereof adapted to receive an end of the bolster therebetween, a plurality of webs extending below the window opening for reinforcing said side frame and provided at their upper edges with a connecting portion extending at an angle thereto and presenting a flat top surface of relatively great area, springs on said side frame on either side of said webs, and a member mounted on said springs and provided with portions interlocking with the bolster and anti-friction elements directly engaging a lower web of said bolster for limited movement laterally of the side frame.

Having thus described my invention, I claim:

1. In a railway truck, in combination, a side frame formed with a compression member, a tension member, struts interposed therebetween and spaced to leave a bolster opening, a bridge wall joining said struts below the bolster opening, those portions of the tension member on opposite sides of said wall being adapted to support springs, bolster springs supported on said portions of the tension member, a bolster supported thereabove by means of said springs, the end of said bolster being freely insertable between the struts, stop lugs on said bolster adapted to be engaged by said struts to limit outward movement thereof, an upper spring cap disposed beneath said bolster, and lateral motion rollers between said bolster and cap, said cap and bolster interlocking to limit inward movement of the latter.
2. In a railway truck, in combination, a side frame formed with a compression member, a tension member, struts interposed therebetween and spaced to leave a bolster opening, a bridge wall joining the lower portions of said struts and decreasing the size of said opening, the tension member being extended transversely on either side of said wall for supporting springs, bolster springs supported on said portions of the tension member, a bolster supported thereabove by means of said springs, said bolster being formed without outer guide lugs whereby the end thereof is freely insertable in the bolster opening, inner stop lugs on said bolster for limiting outward movement thereof, an upper spring cap disposed beneath said bolster and resting on said springs, the upper surface of said cap and the corresponding lower surface of the bolster being adapted to receive rollers, and lateral motion rollers disposed between said bolster and cap.
3. In a railway truck, in combination, a side frame formed with a compression member, a tension member, struts interposed therebetween and spaced to leave a bolster opening, a bridge wall joining the lower portions of said struts for increasing the strength of the frame, said bridge wall restricting the normal size of said opening, those portions of the tension member on opposite sides of said bridge wall being widened for supporting springs, bolster springs supported on said portions of the tension member, a bolster disposed above said springs, the end of said bolster being freely insertable between the struts, inner stop lugs on said bolster adapted to be engaged by said struts to limit outward movement thereof, a spring cap resting on said springs and formed with lugs engaging said struts for limiting lateral movement thereof while allowing vertical movement, and lateral motion rollers disposed between said bolster and cap, interlocking portions being provided on said latter members for limiting relative movement of the bolster while permitting the desired lateral motion thereof.
4. In a railway truck, in combination, a bridge type side frame formed with a relatively small bolster opening above the bridge thereof, bolster springs disposed on opposite sides of said bridge, a spring cap resting on the tops of said springs and interlocked with the frame for preventing lateral movement thereof, rollers supported on said cap, a bolster with its end supported on said rollers and provided with an inner stop lug adapting it for normal transverse movement before said lug engages the frame, said cap being provided with a stop lug engaged by a corresponding shoulder on the bolster for limiting inward movement of the latter.
5. In a railway truck, in combination, a side frame rigidified by a bridge wall connecting the lower portions of the bolster guide columns thereof, springs supported between the bolster and tension member on opposite sides of said bridge wall, a spring cap resting on said springs above said wall, said spring cap being formed with lugs engaging the bolster guide columns for restraining lateral movement of said cap while guiding it for vertical movement, lateral motion rollers resting on said cap, and a bolster resting on said rollers, the movement of said bolster being limited by engagement of upstanding lugs on the cap in corresponding downwardly opening pockets in said bolster.
6. In a railway truck, in combination, a side frame formed with a compression member, a tension member, struts interposed therebetween and spaced to leave a bolster opening, the tension member beneath the bolster opening being adapted to support springs, bolster springs supported on said portions of the tension member, a bolster supported thereabove by means of said springs, the end of said bolster being freely insertable between the struts, stop lugs on said bolster adapted to be engaged by said struts to limit outward movement thereof, an upper spring cap disposed beneath said bolster, and lateral motion rollers between said bolster and cap, said cap and bolster interlocking to limit inward movement of the latter.
7. In a railway truck, in combination, a side frame formed with a compression member, a tension member, struts interposed therebetween and spaced to leave a bolster opening, the tension member being extended transversely beneath the bolster opening for supporting springs, bolster springs supported on said portions of the tension member, a bolster supported thereabove by means of said springs, said bolster being formed without outer guide lugs whereby the end thereof is freely insertable in the bolster opening, inner stop lugs on said bolster for limiting outward movement thereof, an upper spring cap disposed beneath said bolster and resting on said springs, the upper surface of said cap and the corresponding lower surface of the bolster being adapted to receive rollers, and lateral motion rollers disposed between said bolster and cap.
8. In a railway truck, in combination, a side frame formed with a compression member, a tension member, struts interposed therebetween and spaced to leave a bolster opening, those portions of the tension member beneath the bolster opening being widened for supporting springs, bolster springs supported on said portions of the tension member, a bolster disposed above said springs, the end of said bolster being freely insertable at the upper portion of the bolster opening between the struts, a spring cap resting on said springs and formed with lugs engaging said struts for limiting lateral movement thereof while allowing vertical movement, and lateral motion rollers disposed between said bolster and cap, interlocking portions being provided on said latter members for limiting relative movement of the bolster while permitting the desired lateral motion thereof.
9. In a railway truck, in combination, a bridge type side frame formed with a relatively small bolster opening above the bridge thereof, bolster springs disposed on opposite sides of said bridge, a spring cap resting on the tops of said springs

20. In a car truck, a side frame having a central opening with vertical columns at the sides thereof and provided with bolster guiding surfaces, a hollow box-shaped portion of a tension member therebeneath, and adapted to receive an end of the bolster, springs on the box-shaped portion, a spring cap between said bolster and said springs, upstanding flanges on said cap extending beyond said guiding surfaces and received in pockets in said bolster, whereby the latter is normally locked in position and supported for limited movement laterally with respect to the side frame, and means extending from the top of said box-shaped portion for reinforcing said side frame columns and at the same time protecting the springs against oversolid blows.
21. A car truck including a spring plank, springs supported by the plank, a spring cap resting on the springs, rollers carried by the cap, a bolster having one of its ends resting on said rollers, said cap, rollers and bolster being capable of moving up and down as a unit as the bolster load varies, a side frame having an opening into which said parts extend, and elements for interlocking the bolster with the cap and the latter with the side frame, the end of the bolster received in the opening in the frame being narrow enough to clear said frame, permitting detachment of the side frame by a horizontal movement of the latter away from the bolster when the bolster is in the upper portion of the opening, with the springs removed, the spring cap lowered, and the spring plank detached.

22. A car truck including a side frame with columns having generally parallel bolster guiding surfaces and outer and inner surfaces angularly disposed with respect to said generally parallel surfaces, said columns defining a window, spring means supported by a portion of said frame beneath said window, a bolster having its end normally arranged in said window and supported by said spring means and movable lengthwise into and out of said window for assembling and dismembering the truck and also movable vertically in said window while in use, and provided on its opposite vertical sides with vertical recesses, each of which opens downwardly and laterally outward but terminates at its upper end short of the top of the bolster and forms a closure at the upper end of each recess, and a locking member comprising a normally horizontal bar arranged transversely between the underside of the bolster and the upper end of said spring means, and upright arms arranged at opposite ends of said bar and each of said arms having a relatively short inner section which engages with the recess in the respective side of the bolster and a relatively high outer section arranged along the side of the bolster and extending above said short section and disposed with its inner side adjacent the outer surface of the respective column, and said inner section of each arm engaging with the generally parallel bolster guiding surfaces.

GLENN F. COUCH.
